WINDOW LOCK

Louis F. Surridge, Detroit, Mich.

Application March 1, 1946, Serial No. 651,337

2 Claims. (Cl. 292—288)

1

This invention relates to window locks, and particularly to a lock for securing the upper and lower window sashes against opening beyond a predetermined set position.

Window locks have been provided heretofore for securing the windows in predetermined open position against unauthorized further opening. These were usually the type which required the lock to be positively secured by screws, bolts and the like to the sash, which marred the sash and the associated frames with which the lock engaged.

The present invention pertains to a locking device which is secured to the frame of the window without the application of bolts, screws, nails and the like, being disposed angularly in the sash run in which the window sash slides. The device embodies a link which is wedged in the sash run having an arm freely pivoted thereon. When the sash abuts the link it wedges it in the sash run to securely bind it therein, thereby preventing further upward movement of the lower sash. The arm, freely pivoted on the device, engages the upper sash when angularly disposed above a horizontal plane, which prevents the upper sash from being moved downwardly beyond a set position as the arm will bind the sash in its run.

The link and the arm preferably have laterally extending fingers or pins which may have a resilient material applied thereto to prevent marring. The resilient material may be small lengths of rubber tube stretched over the arms, or the arms may have rubber, resin or like material directly adhered thereto through vulcanization or like processes. It was found that a single locking device is all that is required for a window frame having a pair of windows therein and that this device may be removed from any one window and applied to another by simply reversing the rotating movement of the link in the sash run to release it therefrom.

Accordingly, the main objects of the invention are: to provide a locking device for a window which is rigidly secured in position through the force applied thereto by the operation of the window; to provide a locking device having a U-shaped link which is angularly disposed in the slide run in the window frame to be rigidly secured therein when abutted by the window as it is raised to prevent further movement thereof; to apply a freely pivoted arm to the link secured in the sash run of a window frame when abutted by the lower window when raised, which arm engages the face of the upper window above

2

a horizontal plane through the pivot and secures the upper window against downward movement; to apply a resilient material to projecting arms of a locking device which prevents the marring of the frame and sash of the windows when engaged thereby to secure the windows against unauthorized further movement; and, in general, to provide a locking device for a window which is simple in construction, positive in operation, and economical of manufacture.

Other objects and features of novelty of the invention will be specifically pointed out or will become apparent when referring, for a better understanding of the invention, to the following description taken in conjunction with the accompanying drawings, wherein:

Fig. 1 is a broken perspective view of a window frame having an upper and lower window sash locked in position by a locking device embodying features of this invention;

Fig. 2 is a view in elevation of the structure illustrated in Fig. 1, with the upper and lower sash in positive locked position against further downward and upward movement, respectively;

Fig. 3 is a plan view of the structure illustrated in Fig. 2;

Fig. 4 is a sectional view of the structure illustrated in Fig. 3, taken on the line 4—4 thereof;

Fig. 5 is a view of structure, similar to that illustrated in Fig. 2, showing a further form which the invention may assume;

Fig. 6 is a plan view of the structure illustrated in Fig. 5;

Fig. 7 is a view of structure, similar to that illustrated in Fig. 1, showing a still further form of the invention;

Fig. 8 is a plan view of the structure illustrated in Fig. 7, and

Fig. 9 is a view in elevation of the structure illustrated in Fig. 8.

A window of conventional form is illustrated, embodying a frame 1 having sash runs 2 and 3 for a lower window sash 4 and an upper window sash 5, respectively. Locking elements are conventionally employed on the lower part of the upper sash and on the upper part of the lower sash for locking the two sashes in closed position. When, however, it is desired to ventilate a room, the lock is unlatched and the upper window sash is lowered or the lower window sash is raised, or both sashes may be raised and lowered, respectively, depending upon the amount and type of ventilation desired. When the conventional latch is unlocked in this manner, access may be had by anyone from the exterior of the

window into the room being ventilated by raising the lower window sash or lowering the upper window sash. A simple and positive locking device for preventing such unauthorized entrance is therefore very desirable.

The locking device of the present invention embodies a U-shaped link 6 having a web portion 7 and two extending fingers 8, with the web portion 7 disposed angularly to a horizontal plane when the arm portions are disposed in a vertical plane. This angle was found to be approximately 12° to produce the proper binding of the link 6 to the side faces of the sash run 2 when the lowermost finger 8 is contacted by the top of the lower window sash when raised. This produces a slight counterclockwise shifting of the link in the sash run which binds the link therein and rigidly secures it within the run.

A freely pivoted arm 9 is secured by a shoulder rivet 10 to the web portion 7 of the link 6, preferably in off-center relation to the ends of the web portion away from the upper window sash 5, as clearly illustrated in Fig. 3. The arm 9 has a finger 11 extending at right angles thereto in the same direction as the fingers 8 extend from the web 7. The arm 9 is disposed at an angle to the horizontal plane when the finger 11 is disposed in the vertical plane, as clearly illustrated in Fig. 2, the angle being approximately 12°. The finger 11 engages the face of the upper window sash 5 and while permitting a closing movement thereto positively prevents the downward or opening movement thereof because of the angular relation of the arm 9.

The fingers 8 and 11 are provided with a frictional element 12 which may be short portions of a rubber tube or which may be a frictional and nonmarring material such as rubber, plastic and the like, which is directly adhered to the surface of the fingers. The material 12 will not only prevent marring but will provide a frictional grip which will produce the binding of the link 6 to the opposite walls of the sash run 2 and the securing of the finger 11 against the face of the window sash 5. It is contemplated that the link 6 and arm 9 will be shifted two or three degrees when a pressure is applied thereto through the raising of the lower window sash 4 and the lowering of the upper window sash 5 to have the link and arm disposed at approximately 10° to a horizontal plane. This provides a positive binding force to prevent the movement of the lower window sash upwardly and the upper window sash downwardly beyond a desired set position.

By a counterclockwise rotative movement to the link 6, the locking device is released from the window frame and may be shifted to a different position therein or applied to a different frame, as the case may be. It is to be noted, however, that once the locking device is applied to a window, it will remain in position to always prevent the lower window sash from being raised beyond a predetermined desired amount while the upper window sash will similarly be locked against a lowering movement and may be adjusted from time to time by slightly raising the upper window to release the arm 9, and by holding the arm out of contact with the upper window sash, the sash may be further adjusted downwardly. This, however, must be accomplished from the inside of the building as the position of the locking device in the window frame is such as to be out of the reach of any one attempting to gain entrance from the exterior of the building.

Referring to Figs. 5 and 6, a further form of the invention is illustrated, that wherein a link 13 has knurled pins 14 and 15 disposed one at each of its ends for engaging the inner faces of the sash run 2 with the link disposed at an angle to the horizontal. The knurled pin 14 is press-fitted in an aperture in one end of the link 13 on the projecting end of which an arm 16 is freely pivoted and retained thereon by suitable means, 10 herein illustrated as by a screw 17. The arm 16 has on its end opposite to that which is pivoted on the projection of the pin 14, a knurled pin 18 which is disposed in position to engage the inner face of the upper sash 5, with the arm disposed 15 at an angle to the horizontal. The locking element of Figs. 5 and 6 functions the same as the locking element illustrated in Figs. 1 to 4, the link 13 being wedged between the opposite faces of the sash run 2 and the arm 16 being wedged 20 between the end of the link 13 and the face of the window sash 5. The counterclockwise rotation of the link 13 releases it from the sash run, while a clockwise rotation produced manually or by the upward movement of the window sash 4, 25 securely locks the link in the sash run.

Referring to Figs. 7, 8 and 9, a still further form of the invention is illustrated, that wherein a link 19 is of L shape, having a web portion 20 from which a flange 21 is formed from the plane thereof through an angle of substantially 82°. This provides an angle of substantially 98° from the plane of the web 20 and the flange 21 so that the end of the flange will first engage one of the faces of the sash run 2 and lock the link against 35 outward movement therefrom. An aperture 22 is provided through the web portion 20 of the link 19 interjacent its ends, in which a stud 23 on the end of a knurled cylindrical pin 24 is press-fitted, having a portion extending beyond the web portion 20 on which an arm 25 is freely pivoted.

The arm 25 is retained on the end of the stud 23 by "staking" the end of the stud, as at 26, or by any other suitable means. The pin 24 engages one face of the sash run 2, while the end of the 45 flange 21 engages the opposite face when the link is disposed at an angle of approximately 12° with the horizontal. The lower window sash 4 will strike the flange 21 to cause the bar to be rotated counterclockwise and to be more firmly locked in position in the sash run 2. It will be noted that the flange 21 is not only bent angularly to the plane of the web portion 20, but also is twisted relative thereto to be in a vertical plane, as illustrated in Fig. 9, when the web portion 20 is in 55 locking position disposed at an angle of substantially 12° to the horizontal. The arm 25 is bent outwardly at 27 and inwardly to form a finger 28 which is disposed parallel to the face of the upper window sash 5 when the arm 25 is disposed at an angle of substantially 12° to the horizontal. This occurs when the finger 28 or the frictional material 12 thereon is in engagement with the face of the upper window sash 5.

It will be noted further that when in position 65 to lock the upper and lower window sashes, as illustrated in Fig. 9, the web 20 of the link 19 is disposed at an angle of 12° below the horizontal and that the arm 25 is disposed 12° above the horizontal. When the window sash 4 is raised and strikes against the flange 21 of the link 19, the link is urged counterclockwise to be more firmly secured in the sash run 2. When the window sash 5 is locked in position by the arm 25, the further downward movement of the sash 70 75 5 applies a downward force to the pin 24 which

attempts to further rotate the link 19 in a counterclockwise direction to further lock the link within the sash run 2. Thus, the attempt to open either of the window sashes 4 and 5 causes the link 19 to be urged in a counterclockwise direction to be more securely anchored between the faces of the sash run 2.

When the locking device is to be removed from the window frame, the upper window sash is moved upwardly to release the arm 25 and the lower window sash 4 is moved down out of engagement with the flange 21 of the link 19. The device is then grasped by the operator and a force is applied to the extending end 29 thereof which rotates the link clockwise and releases it completely from the faces of the sash run 2 so that it may be removed therefrom. The locking device may again be applied to the same or another window frame by inserting the flange 21 and pin 24 between the faces of the sash run 2 and moving the end 29 downwardly to rotate the link counterclockwise within the sash run. The flange 21 and the pin 24 engage the opposite faces of the run and the link is secured in locked relation therewith, as illustrated in Fig. 9. The raising of the lower window sash 4 against the flange 21 more securely locks the link 19 within the sash run. The engagement of the finger 28 with the face of the upper window sash 5 upon the downward movement of the sash securely locks the sash against further downward movement. The projecting end of the flange 21 prevents the device from being pulled outwardly from the sash run without first being released by a clockwise movement being applied thereto.

It is to be understood that the locking device may be constructed in somewhat different manner from that shown but still fall within the scope of the present invention. For example, the fingers on the end of the link may be adjustable toward and away from each other so as to be bound directly between the opposite faces of the sash run. In a similar manner, the arm may have the end flange adjusted upwardly and inwardly thereon to be forced against the face of the upper window sash to bind it against movement. Broadly, the present invention pertains to a link which may be bound between opposite faces of the sash run and an arm thereon which may be

bound against the face of the upper window sash to lock both sashes against movement beyond a predetermined set position.

What is claimed is:

- 5 1. A locking device for upper and lower sliding window sashes in a window frame including, in combination, a link having a pair of spaced projecting fingers on one side thereof, an arm having a projecting finger on one end thereof, and a pivot for securing the arm in freely pivoted relation to the link on the side opposite to that containing the projecting fingers in a position to engage the face of the upper window sash and to form a binding lock therewith against downward movement when said link fingers are locked in the sash run above the lower sash to limit the upward movement of the lower sash.
- 10 2. A locking device for upper and lower sliding window sashes in a window frame including, in combination, a link having a pair of spaced projecting fingers on one side thereof disposable between the faces of the sash run above the lower sash to limit the upward movement of the lower sash, an arm having a projecting finger on one end thereof, a pivot for securing the arm in freely pivoted relation to the link on the side opposite to that containing said projecting fingers in a position to engage the face of the upper window sash and to form a binding lock therewith against downward movement, and a friction material secured to said fingers for protecting the surfaces of said faces and for aiding in the binding action therewith.
- 15 3. A locking device for upper and lower sliding window sashes in a window frame including, in combination, a link having a pair of spaced projecting fingers on one side thereof disposable between the faces of the sash run above the lower sash to limit the upward movement of the lower sash, an arm having a projecting finger on one end thereof, a pivot for securing the arm in freely pivoted relation to the link on the side opposite to that containing said projecting fingers in a position to engage the face of the upper window sash and to form a binding lock therewith against downward movement, and a friction material secured to said fingers for protecting the surfaces of said faces and for aiding in the binding action therewith.
- 20 4. A locking device for upper and lower sliding window sashes in a window frame including, in combination, a link having a pair of spaced projecting fingers on one side thereof disposable between the faces of the sash run above the lower sash to limit the upward movement of the lower sash, an arm having a projecting finger on one end thereof, a pivot for securing the arm in freely pivoted relation to the link on the side opposite to that containing said projecting fingers in a position to engage the face of the upper window sash and to form a binding lock therewith against downward movement, and a friction material secured to said fingers for protecting the surfaces of said faces and for aiding in the binding action therewith.
- 25 5. A locking device for upper and lower sliding window sashes in a window frame including, in combination, a link having a pair of spaced projecting fingers on one side thereof disposable between the faces of the sash run above the lower sash to limit the upward movement of the lower sash, an arm having a projecting finger on one end thereof, a pivot for securing the arm in freely pivoted relation to the link on the side opposite to that containing said projecting fingers in a position to engage the face of the upper window sash and to form a binding lock therewith against downward movement, and a friction material secured to said fingers for protecting the surfaces of said faces and for aiding in the binding action therewith.
- 30 6. A locking device for upper and lower sliding window sashes in a window frame including, in combination, a link having a pair of spaced projecting fingers on one side thereof disposable between the faces of the sash run above the lower sash to limit the upward movement of the lower sash, an arm having a projecting finger on one end thereof, a pivot for securing the arm in freely pivoted relation to the link on the side opposite to that containing said projecting fingers in a position to engage the face of the upper window sash and to form a binding lock therewith against downward movement, and a friction material secured to said fingers for protecting the surfaces of said faces and for aiding in the binding action therewith.
